MULLING APPARATUS

Ernest A. Hund, Chicago, Ill., assignor to The
Beardsley & Piper Company, Chicago, Ill., a
corporation of Illinois

Application September 14, 1936, Serial No. 100,631

13 Claims. (Cl. 83—45)

The present invention relates generally to apparatus for mulling or mixing granular material. More particularly the invention relates to that type of mulling apparatus which is used in a foundry or like establishment to mull, mix or recondition molding sand and comprises (1) a frame; (2) an open top sand retaining receptacle which is mounted on and supported by the frame and embodies a substantially flat circular bottom and an outwardly bulged side wall which is of substantially semicircular cross-section and is joined to and extends upwardly from the outer margin of the bottom; (3) a plurality of balls which are arranged to travel in a circular course over the bottom and around the side wall of the receptacle and are adapted during such travel to spin and effect the desired mulling, mixing or reconditioning of the sand on the receptacle bottom and between them and the outwardly bulged side wall; and (4) a motor and speed reducing gearing for propelling the balls in the aforementioned circular course.

One object of the invention is to provide a mulling apparatus of this type in which the mulling balls are slightly less in diameter than the outwardly bulged receptacle side wall is in cross-section and are mounted on the lower ends of substantially vertically extending shafts which are pivotally connected by brackets at their upper end to a rotary cross-arm in the central portion of the receptacle so that they support the balls in such manner that during operation of the motor they swing outwards by centrifugal force into a position wherein they are substantially concentrically disposed with respect to the outwardly bulged side wall.

Another object of the invention is to provide a sand mulling apparatus of the last mentioned character which embodies stop means between the brackets and the rotary cross-arm for limiting outward swing of the shafts so that during drive of the cross-arm the balls do not contact with the side wall of the receptacle and remain in a position where they are concentrically disposed with respect to the receptacle side wall.

A further object of the invention is to provide a mulling apparatus which comprises scrapers for scraping the mulled sand from the outwardly bulged side wall of the receptacle and moving it inwards onto the receptacle bottom and deflectors behind the scrapers for deflecting the sand outwards into the path of the mulling balls and effecting a secondary mulling action, and also comprises novel and improved means for supporting the

plows and deflectors for conjoint rotative movement with the mulling balls.

A still further object of the invention is to provide a mulling apparatus of the type and character under consideration in which the outwardly bulged side wall of the receptacle embodies an outwardly swinging door for permitting discharge of the mulled sand from the receptacle, and the deflectors serve in addition to deflecting the sand outwards into the path of the mulling balls to discharge the mulled sand from the receptacle when the door is in its open position.

In addition it is contemplated as one of the objects of the invention to provide a mulling apparatus which is extremely efficient in operation and is an improvement upon that which is described in and forms the subject matter of an application for United States Letters Patent filed concurrently herewith by Walter F. Piper, Serial Number 100,630.

Other objects of the invention and the various advantages and characteristics of the present mulling apparatus will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a view partly in plan and partly in cross-section of a sand mulling apparatus embodying the invention;

Figure 2 is a vertical section taken on the line 2—2 of Figure 1 and showing the arrangement and construction of the ball type mulling elements and the manner in which they are suspended by the substantially vertically extending shafts for outward swinging movement in the direction of the outwardly bulged side wall of the receptacle;

Figure 3 is a detail vertical section through the portion of the receptacle which includes the door for permitting of discharge of the mulled sand;

Figure 4 is a fragmentary side elevational view of the door portion of the receptacle;

Figure 5 is a detail perspective view of one of the scrapers for scraping the sand from the inner face of the bulged side wall of the receptacle;

Figure 6 is a fragmentary perspective of one of the deflectors which operate during drive or operation of the apparatus to deflect the sand outwards into the path of the mulling balls and also

to discharge the mulled sand from the receptacle when the door is open; and

Figure 7 is a detail perspective showing the manner in which the scrapers are mounted for 5 conjoint rotation with the mulling balls.

The apparatus which forms the subject matter of the invention is primarily adapted for use in a foundry or like establishment in connection with the mulling, mixing, or reconditioning of molding sand, and comprises a frame 8, a sand holding or retaining receptacle 9, and a pair of mulling balls 10.

The frame is preferably of two piece design and consists of a cast metal base section 11, and a cast metal top section 12. The base section 11 is elongated and embodies at one end thereof a bed plate 13 for an electric motor 14. At its other end the base section 11 of the frame embodies a continuous wall 15 which extends upwardly and 10 with the top section 12 of the frame defines a gear compartment 16. The top section 12 embodies a top wall 17 and a depending continuous wall 18. The latter rests on the upstanding wall 15 of the base section 11 and is secured in place 15 by means of bolts 19 which, as shown in Figure 2, extend through out-turned abutting flanges 20 on the abutting margins of the two frame sections.

The sand holding or retaining receptacle 9 is mounted on and supported by the frame 8 and 20 consists of a bottom 21, a side wall 22, and an upstanding tubular member 23. The bottom 21 is circular and rests on the top wall 17 of the top section 12 of the frame 8. Bolts 24 extend through the marginal portion of the top wall 17 25 and into the receptacle bottom 21 and serve to hold the receptacle in fixed relation with respect to the frame. The tubular member 23 is centrally disposed with respect to the side wall 22 and is formed integrally with the bottom 21. The lower end of said tubular member is flared 30 and embodies a substantially quadrantly curved outer surface 25 which joins the top face of the bottom and serves to direct the sand which accumulates in, or is drawn toward, the 35 central portion of the receptacle outwards onto the receptacle bottom 21. The upper end of the tubular member 23 projects a slight distance above the upper edge or margin of the side wall of the receptacle. The side wall is substantially 40 semicircular in cross-section and joins the top face of the receptacle bottom 21 in a gradual curve. The inner face of the side wall is slightly greater in diameter than the mulling balls 10. An infundibular or funnel-shaped mouth 26 for 45 receiving sand and directing it into the receptacle for mulling purposes is connected to and formed integrally with the upper margin of the side wall 22. Preferably the receptacle is in the form of a metallic casting. In order to permit 50 of ready discharge of mulled sand from the receptacle, a door 27 is formed in the side wall of the receptacle. This door is shaped conformably to, and forms a part of, the outwardly bulged receptacle side wall and is hinged at the 55 upper end thereof so that it may be swung outwards as shown in dotted lines in Figure 3 of the drawings. The hinged connection whereby the door is pivotally supported comprises a pair of lugs 28 on the upper margin of the door, a 60 pair of lugs 29 on the lower portion of the receptacle side wall, and a rod 30. The lugs 29 are positioned outwardly of, and in substantially abutting relation with, the lugs 28, and the rod 30 extends through aligned holes in the lugs 28 65 and 29. The latch 31 serves to hold the door in 70 its closed position.

This latch is in the form of a bar and is pivotally supported at the central portion thereof by means of a bolt 32 which fits within an internally threaded socket 33 in the central portion of the door. The ends of the latch are adapted to coact with a pair of hook-shaped members 34 and 35. The member 34 faces downwardly and is formed as an integral part of one of the lugs 28 at one side of the door. The hook-shaped member 35 is located at the other side of the door and is secured to the side wall of the receptacle in such manner that it extends upwards. When the door is in its closed position and it is latched in place the latch 31, as shown in Figure 4, extends horizontally and the ends thereof fit respectively in the hook-shaped members 34 and 35. To release the door it is only necessary to rotate the latch so as to disengage the ends thereof from the members 34 and 35. The latch 31 together with the hook-shaped members 34 and 35 constitutes simple means for releasably securing the door in its closed position. In order to protect and form a housing for the side wall of the receptacle a cylindrical metallic skirt 36 is provided. This skirt surrounds the receptacle side wall and is welded or otherwise fixedly secured at the upper margin thereof to the mouth 26. The lower end of the skirt embodies an inturned flange 37 which is fixed to the outer edge of the receptacle bottom 21. A rectangular opening 38 is formed in the skirt in order to permit of manipulation of the latch 31 and outward swinging of the door 27.

The mulling balls 10 are preferably two in number. They comprise metallic cores 39 and solid rubber coverings 40 and are mounted on the lower ends of a pair of substantially vertically extending shafts 41. The shafts, as shown in the drawings, extend through the cores 39 of the balls and have at their lower ends bolts 42 which engage the bottom portions of the cores 39 and prevent downward movement of the balls with respect to the shafts. The upper ends of the shafts are connected by roller bearings 43 to a pair of brackets 44 which, as shown in Figure 2, are pivotally connected by horizontally extending pins 45 to the outer ends of a cross-arm 46 so that they, together with the shafts and mulling balls, are free to swing radially with respect to the sand holding or retaining receptacle 9. The cross-arm 46 is fixedly connected, as hereinafter described, to the upper end of a vertically extending shaft 47, which extends through the tubular member 23 of the receptacle and is driven, as hereinafter described, so as to cause the balls 10 to swing in a circular course around the outwardly bulged side wall 22 of the receptacle. The roller bearings 43 are disposed in cylindrical sockets 48 in the brackets 44 and permit the shafts 41 to rotate about their own axes. As a result of this arrangement the mulling balls are free to spin or rotate during travel around the side wall of the receptacle. The bearings consist of upper sections 43^a and lower sections 43^b. The upper sections 43^a consist of outer races within the upper portions of the sockets 48, inner races around the upper ends of the shafts 41, and rollers between the races, and are arranged and constructed so that the shafts 41 are held against downward axial displacement with respect to the brackets 44. The lower sections 43^b of the roller bearings consist of outer races within the lower portions of the sockets 48, inner races around the upper ends of 70 75 80 85 90 95 98 99 100

the shafts 41 and roller bearings between the inner and outer races and are shaped and constructed, as shown in Figure 2, so that they prevent upward axial displacement of the shafts 41 with respect to the brackets. The upper ends of the sockets 48 are closed by means of caps 49 which are fixedly secured to the top portions of the brackets. The lower ends of the sockets are closed or protected against the ingress of sand by means of caps 50 which are bolted or otherwise secured to the bottom portions of the brackets and support collars 51. The latter, as shown in Figure 2, extend around the portions of the shafts 41 which are between the roller bearings 43 and the upper portions of the cores 39 of the mulling balls. The inner portions of the brackets are tubular in character and fit within forks 52 at the ends of the cross-arm 46. The pins 45 extend through and are journaled in the tubular portions of the brackets and fit within holes in the forks 52. In order to limit outward swinging movement of the shafts 41 and the mulling balls 10, lugs 53 and stop screws 54 are provided. The lugs project upwardly from the inner tubular portions of the brackets and then extend inwardly into overhanging relation with respect to the ends of the cross-arm 46. The stop screws 54 extend through the inwardly extending portions of the lugs and are adapted when brought into abutting relation with the cross-arm to limit outward swinging of the balls. Lock nuts 55 on the upper ends of the screws serve to hold the screws in their various adjusted positions. By adjusting the screws vertically with respect to the lugs 53 the extent of outward swinging of the mulling balls with respect to the side wall of the receptacle may be controlled. By employing the lugs and stop screws the mulling balls may be controlled so that during drive of the shaft 47 in connection with operation of the mulling apparatus the balls do not swing outwards sufficiently far to strike against the bulged side wall 22 of the receptacle. The shafts 41 are inclined upwardly and outwardly, as shown in Figure 2, when the apparatus is at rest, and the balls are mounted on the shafts so that they are positioned a slight distance above the receptacle bottom 21. When the apparatus is operated by driving the shaft 47 and causing the cross-arm 46 together with the mulling balls to rotate around the receptacle, the mulling balls in response to centrifugal action swing outwards towards the receptacle side wall and effect a mulling action that is, squeezing of the sand between them and the side wall of the receptacle. The balls are so arranged and the brackets are so pivoted that when the balls swing outwardly into their operative or mulling position they are substantially concentrically positioned with respect to the side wall of the receptacle. Because the balls are supported by the shafts 41 they are free to rotate while they are moved in a circular course within the receptacle. As the result of rotation of the balls and swinging of the balls in a circular course within the receptacle, the sand is effectively mulled. The solid rubber coverings 40 are spherical and fit over and around the cores 39. By reason of the fact that the covers are formed of solid rubber the sand is yieldingly or elastically gripped for mulling purposes during operation of the apparatus. By reason of the fact that the shafts 41 are upwardly and outwardly inclined when the apparatus is at rest the balls, when the apparatus is set into operation, swing downwards and out-

wards and then upwards toward the outwardly bulged lower portion of the receptacle side wall. Because of this action the sand on the receptacle bottom 21 is urged outwards into the outwardly bulged portion of the receptacle where it is subjected to the mulling action of the balls 10. As a result of the fact that the balls rotate during travel in their circular course within the receptacle, the sand on the receptacle bottom 21 as well as the sand within the outwardly bulged lower portion of the receptacle side wall 22 is subjected to mulling.

The upper end of the vertically extending shaft 47 is provided with a polygonal stem 56 and embodies a shoulder 57 beneath the stem. 18 As shown in Figure 2, the stem fits within a polygonal socket 58 in the central portion of the cross-arm 46 and form a driving connection between the shaft and the cross-arm whereby when the shaft is driven the cross-arm together 20 with the shaft 47 and the mulling balls 10 is rotated bodily around the receptacle 9. The central portion of the cross-arm rests on the shoulder 57 and is locked in place by means of a cap 59 which overlies the central portion of the 25 cross-arm and is clamped or urged in a downward direction by means of a bolt 60 which extends through the cap 59 and fits within an internally threaded socket in the polygonal stem 56. The upper end of the shaft 47 is journaled 30 in a roller bearing 61 and the lower end of the shaft is supported and journalled in a roller bearing 62. The bearing 61 consists of an outer race within the upper end of the upstanding tubular member 23 of the receptacle 9, an inner race around the upper end of the shaft 47, and an annular series of rollers between the two races. The races and rollers of the bearing 61 are arranged and constructed so as to hold the shaft against upward axial displacement with 35 respect to the tubular member 23. The roller bearing 62 is constructed and arranged to hold the shaft 47 against downward axial displacement and consists of an outer race within a hub-like member 63 on the base section 11 of the 40 frame 8, an inner race around the lower end of the shaft 47 and an annular series of rollers between the two races. The hub-like member 63 is disposed in the gear compartment 16 and is 45 formed as an integral part of the base section 11 of the frame.

The shaft 47 together with the cross-arm and the mulling balls is driven by the electric motor 14 through the medium of speed reducing gearing. This gearing is disposed in the gear compartment 16 in the frame 8 and consists of a bevel pinion 64, a bevel gear 65, a pinion 66, and a gear 67. The bevel pinion 64 is mounted on one end of a horizontally extending shaft 68. The latter is journaled in suitable roller bearings 60 within a sleeve 69 between the base and top sections 11 and 12 of the frame and is connected by a coupling 70 to the armature shaft of the electric motor 14. The bevel gear 65 meshes with, and is driven by, the bevel pinion 64 and is keyed or otherwise fixedly secured to a vertically extending shaft 71 which is journaled in and held against axial displacement by a roller bearing 72 and a roller bearing 73. The upper bearing 72 is mounted in a socket in the top wall 17 of the 70 top section 12 of the frame and the lower bearing is mounted in a cylindrical socket in the base section 11 of the frame. The pinion 66 is keyed or otherwise fixedly secured to the shaft 71 and is disposed between the bevel gear 65 and the 75

roller bearing 72. The gear 67 is fixed to the lower end of the shaft 47 and meshes with and is driven by the pinion 66. When the motor 14 is supplied with current it operates through the 5 medium of the speed reducing gearing within the compartment 16 to drive the shaft 47 which in turn swings or rotates the cross-arm 46, the shafts 41 and the mulling balls 10.

In order to effect aeration and a secondary 10 mulling of the sand within the receptacle 9 and also to control the sand so that the entire batch or mass is subjected to the action of each mulling ball during each revolution of the cross-arm 46, a pair of scrapers 74 and a pair of deflectors 15 15 are provided.

The scrapers are located directly behind the mulling balls 10 and serve during drive of the cross-arm 46 to scrape the mulled sand from the inner periphery or face of the outwardly bulged 20 side wall of the receptacle and to project or direct the sand inwardly toward the central portion of the receptacle bottom 21. They are mounted on the outer ends of a pair of radially extending angle iron bars 76 and comprise scraping parts 74^a and sand projecting parts 74^b. The scrapers are preferably in the form of plate metal stampings. The scraping parts 74^a of the scrapers are positioned adjacent to the lower portion of the side wall of the receptacle and 25 have the outer edges thereof shaped or curved conformably to the inner periphery of the receptacle side wall. As shown in Figures 3 and 5 the scraping parts of the scrapers extend from the bottom 21 of the receptacle to the funnel 30 shaped mouth 26 and are curved or rounded so that during drive or operation of the apparatus they scrape the mulled sand from the inner face of the outwardly bulged lower portion of the receptacle side wall 22 and deflect it toward the 35 projecting parts 74^b. The latter extend inwardly and rearwardly with respect to the lower ends of the scraping parts 74^a and overlie the receptacle bottom 21. They project at approximately 45° angles with respect to the angle iron bars 76 40 and operate to deflect or direct the scraped mulled sand toward the central portion of the receptacle bottom. The angle iron bars 76 are attached to a cylindrical skirt 77 on the cross-arm 46 by means of brackets 78 and comprise 45 vertically extending webs 76^a and horizontally extending webs 76^b. The webs 76^b are formed integrally with the vertically extending webs and project laterally from the bottom margins of the latter. The brackets 78 are bolted against 50 diametrically opposite flat faces on the skirt 77 and embody flanges which lap the inner ends of the vertical and horizontal webs of the angle iron bars 76. Bolts 79 extend through the inner ends of the horizontally extending webs of the 55 angle iron bars and serve to secure the bars in fixed relation with respect to the brackets 78. The scrapers 74 are fixedly connected to the outer ends of the angle iron bars 76 by a pair of angle brackets 80 and a pair of angle brackets 60 65 81. The angle brackets 80 are riveted or otherwise fixedly secured to the outer ends of the vertical web 76^a of the angle iron bars 76 and embody horizontally extending bottom flanges 80^a which extend horizontally and are flush with the 70 outer ends of the horizontally extending webs 76^b of said angle bars 76. The angle brackets 81 embody vertically extending flanges 81^a and horizontally extending flanges 81^b. The vertical flanges of these last mentioned brackets fit 75 against the inner face of and are riveted to the

inner central portion of the scraping part 74^a of the plow. The horizontally extending flanges 81^b of the brackets 81 extend inwardly from the upper ends of the flanges 81^a and underlie and are bolted to the bottom flanges 80^a of the brackets 80 and the horizontally extending webs 76^b of the bars 76. The skirt 77 to which the brackets 78 are attached is formed as an integral part of, and depends from, the central portion of the cross-arm 46 and surrounds the upper end 10 of the tubular member 23 of the sand holding or retaining receptacle 9.

The deflectors 75 are located behind the scrapers 74 and extend outwards from the skirt 77 on the central portion of the cross-arm 46. They are preferably formed of plate metal and are secured to a pair of diametrically opposite flat faces 82 on the skirt 77 by means of angle brackets 83. The brackets, as shown in Figures 3 and 6, are bolted to the deflectors and also to the 20 aforementioned flat faces 82. The deflectors extend upwardly from the receptacle bottom 21 to a point adjacent to the mouth 26 of the receptacle and are angled so that they serve to deflect the sand outwards into the path of the mulling 25 balls, and also to discharge the mulled sand through the door opening in the outwardly bulged lower portion of the side wall of the receptacle when the door 27 is in its open position. When the apparatus is in operation at a normal speed of 30 approximately 90 R. P. M. the deflectors due to their size and shape fling the sand outwards towards the sides of the receptacle and effect aeration of the sand. By reason of the fact that the deflectors extend from the tubular member 23 to 35 a point slightly inwards of the side wall of the receptacle the sand is so controlled that the entire batch or mass is subjected to the action of each mulling ball during each revolution of the cross-arm 46 and hence the sand is uniformly 40 mulled. Aeration of the sand is attributable to the fact that the deflectors 75 project the sand outwards in a scattered manner and the sand is maintained in more or less suspension prior to being squeezed by the mulling balls. 45

When it is desired to mull sand with the apparatus, the sand to be mulled is shoveled or otherwise delivered into the mouth 26. The latter, as hereinbefore described, serves to direct the sand into the central portion of the receptacle 9. When the electric motor 14 is started by supplying it with electric current, the shaft 47 is driven through the medium of the speed reducing gearing in the gear compartment 16 and in turn drives the cross-arm 46, the shafts 41 and the 50 mulling balls 10. During drive of the cross-arm the mulling balls move in a circular course around the inside of the receptacle and in response to centrifugal force swing outwards toward the outwardly bulged side wall 22 of the receptacle and mull the sand between them and said portion of the receptacle. During swinging of the balls around the receptacle they rotate and effect the desired mulling action of the sand on the receptacle bottom and within the receptacle side wall. The sand which is squeezed or compressed against the inner face of the outwardly bulged lower portion of the side wall of the receptacle as the result of the action of the 55 mulling balls 10 is scraped clear of the receptacle side wall and directed inwards toward the center of the receptacle bottom by the action of the scrapers 74. After being directed inwards the sand encounters the deflectors 75 and is moved 60 65 70 75 80 85 90 95 100

or directed outwards in a scattered manner into the path of the balls. The apparatus is driven until the sand within the receptacle is mulled to the proper extent. At the conclusion of the mulling operation the door 27 is released and swung into its open position. When the apparatus is driven with the door open the deflectors 75, as hereinbefore described, force the mulled sand outwards through the door opening. By reason of the fact that outward swinging of the mulling balls 10 and the resultant mulling effect is due to centrifugal force it is manifest that when the apparatus is driven at a high rate of speed a more aggressive and quicker mulling action is obtained than when the apparatus is driven at a lower speed and the mulling balls, due to the reduced centrifugal action, are flung or swung outwards against the outwardly bulged lower portion of the side wall of the receptacle with less force. Because the mulling action is attributable to centrifugal force and not the weight of the mulling balls the balls need not be extremely heavy and of solid metal.

The herein described mulling apparatus is extremely efficient in operation and may be manufactured at a comparatively low and reasonable cost.

The invention is not to be understood as restricted to the details set forth, since these may be modified within the scope of the appended claims, without departing from the spirit and scope of the invention.

Having thus described the invention what I claim as new and desire to secure by Letters Patent is:

1. In a mulling apparatus of the character described, the combination of an open top receptacle adapted to contain the material to be mulled and comprising a substantially flat circular bottom and an annular side wall extending upwardly from the outer marginal portion of the bottom, a revolvable cross-arm extending horizontally across the upper portion of the receptacle, a substantially vertical shaft connected to and depending from one end of the cross-arm and positioned adjacent to said side wall, a rotary mulling element mounted on the lower end of the shaft so that during drive of the cross-arm it travels in a circular course around the side wall of the receptacle and in addition spins or rolls and squeezes the material between it and the receptacle side wall, power means for driving the cross-arm, and means connected to the cross-arm for conjoint drive therewith for controlling the material so that during each time the element travels around the side wall substantially the entire mass of material is flung outwards in a scattered and aerated manner against substantially all portions of the inner face of said side wall into the path of the element and is then after squeezing and resultant mulling by the element scraped and deflected inwards.

2. In a mulling apparatus of the character described, the combination of an open top receptacle adapted to contain the material to be mulled and comprising a substantially flat circular bottom and an annular outwardly bulged side wall of substantially semicircular cross-section, joined by a gradual curve to the outer margin of the bottom and extending outwardly and upwardly and then inwardly, a revolvable cross-arm extending horizontally across the upper portion of the receptacle, a substantially vertical shaft depending from one end of the cross-arm and positioned adjacent to the side wall, a freely ro-

tatable substantially truly spherical mulling ball with a diameter slightly less than the cross-sectional diameter of the receptacle side wall, mounted on the lower end of the shaft so that during drive of the cross-arm it travels in a circular course around the side wall of the receptacle and in addition spins or rolls and squeezes the material between it and the receptacle bottom and between it and the receptacle side wall, power means for driving the cross-arm, and means connected to the cross-arm for conjoint drive therewith for controlling the material so that during each time the ball travels around the side wall substantially the entire mass of material is flung outwards in a scattered and aerated manner against substantially all portions of the inner face of said side wall into the path of the ball and is then after squeezing and resultant mulling by the ball scraped and deflected inwards.

3. In a mulling apparatus of the character described, the combination of an open top receptacle adapted to contain the material to be mulled and comprising a substantially flat circular bottom and an annular outwardly bulged side wall joined by a gradual curve to the outer margin of the bottom and extending upwardly and outwardly and then inwardly, a revolvable cross-arm extending horizontally across the upper portion of the receptacle, a substantially vertical shaft depending from the end of the cross-arm and positioned adjacent to the side wall, a bracket connected to the upper end of the shaft and connected pivotally to one end of the cross-arm in such manner that the shaft extends downwardly and inwardly over the receptacle bottom when the cross-arm is at rest and is free to swing outwards toward the side wall of the receptacle when the cross-arm is driven, a rotary mulling ball mounted on the lower end of the shaft so that during drive of the cross-arm it travels in a circular course and swings outwards over the receptacle bottom and towards the receptacle side wall in response to centrifugal force and also spins or rolls and squeezes the material between it and the receptacle side wall, power means for driving the cross-arm, and means connected to the cross-arm for conjoint drive therewith for controlling the material so that during each time the ball travels around the side wall substantially the entire mass of material is flung outwards in a scattered and aerated manner against substantially all portions of the inner face of said side wall into the path of the ball and is then after squeezing and resultant mulling by the ball scraped and deflected inwards.

4. In a mulling apparatus of the character described, the combination of an open top receptacle adapted to contain the material to be mulled and comprising a substantially flat circular bottom and an annular side wall extending upwardly from the outer margin of the bottom, a revolvable cross-arm extending horizontally across the upper portion of the receptacle, a substantially vertical shaft depending from one end of the cross-arm and positioned adjacent to the side wall, a bracket connected to the upper end of the shaft and attached pivotally to said one end of the cross-arm in such manner that the shaft is free to swing outwards toward the receptacle side wall when the cross-arm is driven, a rotary mulling element mounted on the lower end of the shaft so that during drive of the cross-arm it travels in a circular course around the side wall of the receptacle and swings outwards towards said side wall in response to centrifugal force.

force and in addition spins or rolls as the result of contact with the material and squeezes the material between it and said receptacle side wall, adjustable stop means for limiting outward

- 5 swinging of the shaft so that during drive of the cross-arm the element is not in contact with said side wall of the receptacle, power means for driving said cross-arm, and means connected to the cross-arm for conjoint drive therewith for controlling the material so that during each time the ball travels around the side wall substantially the entire mass of material is flung outwards in a scattered and aerated manner against substantially all portions of the inner face of said side wall into the path of the element and is then after squeezing and resultant mulling by the element scraped and deflected inwards.

5. In a mulling apparatus of the character described, the combination of an open top receptacle adapted to contain the material to be mulled and comprising a substantially flat circular bottom and an annular outwardly bulged side wall joined to and extending upwardly from the outer margin of the bottom, a revolvable cross-arm extending horizontally across the upper portion of the receptacle and having a fork at one end thereof and adjacent to the side wall, a substantially vertical shaft depending from the forked end of the cross-arm, a bracket connected to the upper end of the shaft and having the inner portion thereof disposed within the fork and connected by a pivot pin to the bifurcations of the latter so that the shaft is free to swing outwards towards the receptacle side wall when the cross-arm is driven, a rotary mulling ball mounted on the lower end of the shaft so that during drive of the cross-arm it travels in a circular course around said side wall and swings outwards towards the side wall of the receptacle in response to centrifugal force and spins or rolls and squeezes the material between it and the side wall of the receptacle, adjustable stop means adapted to limit outward swing of the shaft so that during drive of the cross-arm the ball does not contact with the receptacle side wall and comprising a lug connected to and extending upwardly and inwardly from the inner portion of the bracket and a substantially vertical screw extending downwardly through the inwardly extending portion of the lug into contact with the base portion of the fork of the cross-arm and accessible from above for adjustment purposes, and means for driving the cross-arm.

6. In a mulling apparatus of the character described, the combination of a receptacle adapted to contain the material to be mulled and comprising a circular bottom and an annular side wall extending upwardly from the outer margin of the bottom, a door in and forming a part of said annular side wall of the receptacle and adapted when opened to permit of lateral discharge of the mulled material from the receptacle, a rotary mulling element mounted to travel in a circular course around the interior of the receptacle side wall so that during such travel it spins or rolls in response to contact with the material and effects mulling of the material between it and said side wall, means for propelling the mulling element in said circular course, and a deflector connected for conjoint travel with the mulling element and arranged and adapted to deflect the material on the receptacle bottom outwardly into the path of the element during a mulling operation and also to fling the mulled

material from the receptacle when said door is open for discharging purposes.

7. In a mulling apparatus of the character described, the combination of an open top receptacle adapted to contain the material to be mulled and comprising a substantially flat circular bottom and an annular outwardly bulged side wall extending upwardly and outwardly and then inwardly from the margin of the bottom, an outwardly swinging door in and forming a part of said outwardly bulged side wall and adapted when opened to permit of lateral discharge of the mulled material from the receptacle, a mulling ball mounted to travel in a circular course around the side wall of the receptacle and so that during such travel it spins or rolls in response to contact with the material and effects mulling of the material between it and said side wall, means for propelling the ball in said circular course, and a deflector connected for conjoint travel with the mulling ball and arranged and adapted to deflect the material on the receptacle bottom outwardly against the side wall and into the path of the ball during a mulling operation and also to fling the mulled material from the receptacle when said door is open for discharging purposes.

8. In a mulling apparatus of the character described, the combination of an open top receptacle adapted to contain the material to be mulled and comprising a substantially flat circular bottom with an upstanding tubular member in the central portion thereof, and an annular outwardly bulged side wall joined to and extending upwardly from the margin of the bottom, a revolvable cross-arm extending horizontally across the central portion of the receptacle and provided at the central portion thereof with a depending skirt encircling the upper end of said tubular member, substantially vertically extending shafts depending from the ends of the cross-arm and positioned adjacent to the side wall, brackets connected to the upper ends of the shafts and pivotally attached to the ends of the cross-arm so that the shafts are free to swing outwards towards the receptacle side wall during drive of the cross-arm, rotary mulling balls mounted on the lower ends of the shafts and so that during drive of the cross-arm they travel in a circular course around the receptacle side wall and swing outwards towards the side wall in response to centrifugal force and in addition spin or roll as the result of contact with the material and squeeze the material between them and said side wall of the receptacle, means for driving the cross-arm comprising a vertically extending shaft extending through the tubular member and connected at its upper end to the central portion of the cross-arm, and deflectors in front of the balls, connected to and radiating from the skirt and shaped so that during drive of the cross-arm they deflect the material on the receptacle bottom outwardly into the path of the balls.

9. In a mulling apparatus of the character described, the combination of an open top receptacle adapted to contain the material to be mulled and comprising a substantially flat circular bottom with an upstanding tubular member in the central portion thereof, and an annular outwardly bulged side wall joined to and extending upwardly from the margin of the bottom, a revolvable cross-arm extending horizontally across the central portion of the receptacle and provided at the central portion thereof with a depending skirt encircling the upper end of said tubular member, substantially vertically extending shafts depend-

ing from the ends of the cross-arm and positioned adjacent to said side wall, brackets connected to the upper ends of the shafts and pivotally attached to the ends of the cross-arm so that the shafts are free to swing outwards towards the receptacle side wall during drive of the cross-arm, rotary mulling balls mounted on the lower ends of the shafts so that during drive of the cross-arm they travel in a circular course around the receptacle side wall and swing outwards towards the side wall in response to centrifugal force and in addition spin or roll as the result of contact with the material and squeeze the material between them and said side wall of the receptacle, means for driving the cross-arm comprising a vertically extending shaft extending through the tubular member and connected at its upper end to the central portion of the cross-arm, and scraper type plows behind the balls connected by bars and brackets to the skirt and shaped so that during drive of the cross-arm they scrape the mulled sand from the inner face of the receptacle side wall and direct it inwards over the receptacle bottom.

10. In a mulling apparatus of the character described, the combination of an open top receptacle adapted to contain the material to be mulled and comprising a substantially flat circular bottom and an annular side wall extending upwardly from the margin of the bottom, an outwardly swinging door in and forming a part of said side wall and adapted when opened to permit of lateral discharge of the mulled material from the receptacle, a revolvable cross-arm extending horizontally across the upper portion of the receptacle, a substantially vertical shaft depending from one end of the cross-arm and positioned adjacent to the side wall, a bracket connected to the upper end of the shaft and pivotally attached to said one end of the cross-arm so that the shaft is free to swing outwardly toward the receptacle side wall when the cross-arm is driven, a rotary mulling element mounted on the lower end of the shaft so that during drive of the cross-arm it swings outwards and travels in a circular course around the side wall and also spins or rolls and squeezes the material between it and the side wall of the receptacle, stop means for limiting outward swing of the shaft so that during drive of the cross-arm the element does not contact with the side wall of the receptacle, means for driving the cross-arm, and a deflector connected to said cross-arm for conjoint travel with the element and arranged and shaped so as to deflect the material on the receptacle bottom outwardly into the path of the element during a mulling operation and also to fling the mulled material from the receptacle when said door is open for discharging purposes.

11. A mulling apparatus comprising in combination a receptacle adapted to contain the material to be mulled and comprising a substantially flat circular bottom and an annular side wall extending upwardly from the margin of the bottom, a revolvable cross arm extending horizontally across the upper portion of the receptacle, an elongated member pivotally connected at one end thereof to the cross arm so that it is free to swing outwards toward the side wall, a rotary mulling element mounted on the distal end of said member and adapted during drive of the cross arm to travel in a circular course around the receptacle side wall and in addition to spin

or roll and squeeze the material between it and the receptacle side wall, power means for driving the cross arm, and means connected to the cross arm for conjoint drive therewith for controlling the material so that during each time the element travels around the side wall substantially the entire mass of material is flung outwards in a scattered and aerated manner against substantially all portions of the inner face of said side wall into the path of the element and is then after squeezing and resultant mulling by the element scraped and deflected inwards.

12. A mulling apparatus comprising in combination a receptacle adapted to contain the material to be mulled and comprising a substantially flat circular bottom and an annular side wall extending upwardly from the margin of the bottom, a revolvable cross arm extending horizontally across the upper portion of the receptacle, an elongated member pivotally connected at one end thereof to the cross arm so that it is free to swing outwards toward the side wall, a rotary mulling element mounted on the distal end of said member and adapted during drive of the cross arm to travel in a circular course around the receptacle side wall and in addition to spin or roll and squeeze the material between it and the receptacle side wall, stop means between the member and said cross arm for limiting outward swinging of said member so that during drive of the cross arm the element is not in contact with said side wall of the receptacle, power means for driving the cross arm, and means connected to the cross arm for conjoint drive therewith for controlling the material so that during each time the element travels around the side wall substantially the entire mass of material is flung outwards in a scattered and aerated manner against substantially all portions of the inner face of said side wall into the path of the element and is then after squeezing and resultant mulling by the element scraped and deflected inwards.

13. A mulling apparatus comprising in combination a receptacle adapted to contain the material to be mulled and comprising a circular bottom and an annular side wall extending upwardly from the margin of the bottom, a door in and forming a part of the receptacle side wall and adapted to be swung open to permit the mulled sand to be discharged laterally from the receptacle, a revolvable cross arm in the central portion of the receptacle, an elongated member connected pivotally at one end thereof to the cross arm so that it is free to swing outwards, a rotary mulling element mounted on the distal end of the member and adapted during drive of the cross arm to swing outwards and travel in a circular course around the side wall and also to spin or roll and squeeze the material between it and said receptacle side wall, stop means for limiting outward swinging of the element so that during drive of the cross arm the element does not contact with the side wall of the receptacle, and a deflector connected to said cross arm for conjoint travel with the element and arranged and shaped so as to deflect material on the receptacle bottom outwardly into the path of the element during mulling operation and also to fling the mulled material from the receptacle when said door is open for discharging purposes.

ERNEST A. HUND.
